UNITED STATES PATENT OFFICE.

ARTHUR ERNEST JERRAM, OF LEICESTER, ENGLAND, ASSIGNOR TO UNITED SHOE MACHINERY COMPANY, OF PATERSON, NEW JERSEY, A CORPORATION OF NEW JERSEY.

SHOE-SUPPORTING JACK.

1,202,293.

Specification of Letters Patent.

Patented Oct. 24, 1916.

Application filed December 16, 1913. Serial No. 807,085.

To all whom it may concern:

Be it known that I, ARTHUR E. JERRAM, a subject of the King of Great Britain, residing at Leicester, in the county of Leicestershire, England, have invented certain new and useful Improvements in Shoe-Supporting Jacks; and I do hereby declare the following to be a full, clear, and exact description of the invention, such as will enable others skilled in the art to which it appertains to make and use the same.

The present invention relates to work supports for lasted boots or shoes, and more particularly to devices of this character employed in connection with sole leveling machines.

It frequently happens that these machines operate upon constantly varying sizes of shoes, and as the work support must be separately adjusted for each different size, a considerable degree of care and skill upon the part of the operator is required to position the shoe properly upon the jack in addition to the usual operation of jacking the shoe.

The object of the present invention is to relieve the operator of the necessity of adjusting the jack for varying sizes of shoes and to perform the various adjustments of the jack automatically in connection with the jacking of the shoe.

With this object in view, a feature of the invention contemplates the provision in a jack of the usual type having a toe post and a heel post relatively movable toward and from one another, of mechanism for automatically positioning the shoe upon the jack in a predetermined relation to the operating tool, and for next clamping the shoe in its adjusted position upon the jack.

A further feature of the invention consists in the provision of relatively movable toe and heel posts, a single jacking lever, and operative connections for causing a continued movement of the lever to first relatively move the toe and heel posts to adjust the shoe upon the jack in a predetermined relation to the operating tool, and for next clamping the shoe in this position.

In the illustrated embodiment of the invention the shoe is automatically adjusted in a predetermined vertical and longitudinal position with relation to the operating tool prior to the clamping of the shoe in position in order to properly position the

sole of the shoe irrespective of the length of the shoe or the depth of the last.

Still further features of the invention consist in certain novel features of construction, combinations and arrangements of parts hereinafter described and claimed; the advantages of which will be obvious to those skilled in the art from the following description.

In the accompanying drawings illustrating the preferred form of the invention, Figure 1 represents a side elevation of the jack, with its various parts in the position they assume when ready for the reception of the shoe; Fig. 2 is a view similar to Fig. 1, with the parts in the position they occupy when the shoe is clamped in position; Fig. 3 is a view similar to Fig. 2, illustrating the alteration effected in the position of the parts when a shoe of shorter length is jacked; Fig. 4 is a detail illustrating the construction of the locking means for the last carrier; Fig. 5 is a detail illustrating a plan view of the mechanism for varying the extent of traverse of the leveling roll and jack; and Figs. 6 and 7 are details illustrating a plan and elevation respectively of a modified construction for locking the last carrier in operative position.

According to the present invention, the lasted shoe is held rigidly in position by a toe rest 1, a last pin 3, and a heel clamp 5, the last pin 3 being forced upwardly and canted with its carrier or heel post 6 so that the heel seat of the shoe is forced upwardly against the heel clamp 5 and at the same time the toe of the shoe is pressed downwardly on the toe rest 1.

In order to accommodate toes of varying heights, the toe rest 1 is supported yielding, the toe of the shoe being inserted by the operator between the toe rest and the underside of a suitable type of gaging device (not shown) in order to permanently position the toe portion of the sole at a predetermined height. After the toe rest has been depressed the required amount, and prior to the movement of the jack beneath the leveling roll, mechanism is provided for automatically locking the toe rest against further downward movement during the operation of the machine. In the illustrated embodiment of the invention the toe rest 1 is mounted upon a stem 7 which projects downwardly into a recess 8 formed in the

5 toe rest supporting post 9 and is yieldingly sustained in an elevated position by a spring 11 located in the bore 12 of the stem 7 and interposed between the top of the bore and a pin 13 extending across the recess 8. The mechanism for locking the toe rest comprises a roll 15 positioned between the outer surface of the stem 7 and a hardened inclined surface 17 located in a hollow in 10 the toe supporting post 9. It will be noted from an inspection of Fig. 2 that the direction of the inclined surface 17 is such that if the roll 15 is free to move it will fall into position to lock the rest 1 against downward movement, and in order to lift the roll at certain predetermined intervals, for example when the work is inserted, a thrust rod is provided. The thrust rod is automatically operated at the proper time to raise the roll 15 and unlock the toe rest in order that it will be free to assume the position determined by the height of the toe before it is again locked in position.

20 The toe rest supporting post 9 extends downwardly and is fulcrumed upon the machine frame 20 at 21. The jack, as a whole, rocks about the axis 21 which is located at a distance from the leveling tool to coincide with the center of the arc which conforms most closely to the mean longitudinal curvature of the tread face of the shoe sole. The other parts of the jack are all connected directly or indirectly with the supporting post 9 and consequently the jack 25 swings, as a whole, upon the main fulcrum 21 to traverse the work beneath and in contact with the leveling roll 23.

30 In order to position the heel seat of the shoe correctly, the heel clamp 5 is carried on an upwardly extending arm 25 which is provided with a gaging face arranged to contact with the counter of the shoe at the heel. The arm 25 is mounted upon a projection 27 extending outwardly from the toe supporting post 9 so that the heel clamp 5 may swing toward or from the toe rest 1 to accommodate lasts of different lengths. The arm 25 is fulcrumed upon the projection 27 at 30 and it will be noted from an inspection 35 of the drawings that the fulcrum about which the heel clamp turns is located nearer the face of the sole than the main fulcrum 21. The curvature of the heel seat does not conform with the curvature of the shank and ball portions of the sole, but rather conforms to an arc of shorter radius than the arc of curvature of the tread face or ball portion of the sole. With the present construction the heel clamp is enabled to accommodate itself to the extreme heel end of the sole, even though this portion of the sole does not conform in general curvature to the rest of the sole. The heel gage is first advanced to engage with the counter of 40 the shoe by a hand lever 32 which also

effects automatically, and in the proper sequence, the locking of the heel gage against backward movement, the locking of the toe rest against downward movement, and the raising and tilting of the last pin 45 carrier 6 to cause the shoe to be locked in the jack. The movement of the jack in relation to the operating means locks the support of the last pin carrier 6 so that the downward thrust upon the sole during the 50 leveling operation shall have no tendency to cant the last pin and split the last.

To effect the advancing movement of the heel gage the jacking lever 32 is constructed and arranged to initially act as a lever of the first class and to finally shift its fulcrum and act as a lever of the second class. The lever 32 is fulcrumed between its ends at 35, and is connected at the end opposite its handle to an arm 36 through a link 37. The arm 36 55 is pivoted at 38 upon the arm 25, thus causing the heel gage to be swung about the fulcrum 30 as the handle of the jacking lever 32 is elevated. This movement causes the heel gage to first contact with the counter of the shoe, and to next push upon the shoe until the toe is correctly positioned upon the toe rest 1. A continued movement of the jacking lever then rocks the arm 36 about the fulcrum 38 against the action of the spring 60 pressed plunger 40 which engages with the stop face 41 formed upon the end of the arm 36. This movement causes the toothed block 42 secured to the arm to engage with a toothed segment 43 secured to the toe supporting post 9. Normally the toothed block 42 is maintained just clear of the segment 43 by the spring pressed plunger 40 and the stop face 45, which determines the position of the arm 36. The arm 25 carrying the heel clamp may be moved freely backward and forward within limits determined by a pin 46 projecting from the toothed segment 43 and arranged to engage a toe 48 formed upon the toothed block 42. The jacking lever 32 is fulcrumed at 35 upon a pivot member 50, which in turn is fulcrumed at 51 upon an arm 53 forming an extension of the toe supporting post 9. The pivot member 50 extends beyond the fulcrum 35 at which the lever 32 is centered, and is connected at its end by a link 55 with a rearwardly projecting portion 56 of the last pin carrier 6. The last pin carrier is fulcrumed at 58 upon the upper end of a yieldingly mounted rod 60 which is normally maintained in an elevated position by a spring, but may be locked in position as hereinafter described. The pivot member 50 is provided with an extension 61 carrying a toothed segment 62 70 which is engaged by a locking latch 65 controlled by a finger lever 66 carried on the handle of the jacking lever 32 so that the parts may be locked in their adjusted position. With the foregoing arrangement the 75

jacking lever 32 when first raised turns on its fulcrum 35, bringing the heel gage into contact with the counter of the shoe at the heel, and next pushing the shoe toe fully 5 into contact with the toe rest, finally locking the heel gage and toe rest in position. Thereafter, the independent movement of the lever 32 is prevented by the engagement of the toothed block 42 with the segment 43 10 and the lever then turns about its end which is connected to the link 37, thus turning the pivot member 50 upon its fulcrum 51 and through the link 55 the last pin carrier is then rocked to bring the heel seat of the 15 shoe into contact with the under side of the heel clamp 5 and press the toe against the toe rest 1. The pivot member 50 is also provided with a stop or abutment 70 formed upon its lower end, which engages with a 20 coöperating stop face 71 formed on the lever 32, the provision of these stops insuring that in unjacking the shoe the jacking lever can not be moved beyond the toothed segment.

As stated heretofore, the toe rest 1 is provided with a lock comprising a roll 15 which is arranged to prevent downward movement of the toe rest unless the roll is acted upon by a releasing rod 73. When the parts of the jack are in their inoperative position, as 25 shown in Fig. 1, the rod 73 is arranged to lift the roll 15 from the inclined surface 17 and leave the toe rest 1 free to move so that it may assume a position governed by the height of the toe. As soon as the lever 32 30 is operated to effect the turning of the heel pin carrier this releasing rod 73 is removed from contact with the roll so that the latter will engage the inclined surface 17 and stem 7, and thus lock the toe rest in its adjusted 35 position. To this end a tappet screw 75 is threaded in a boss formed on the pivot member 50 and engages with an abutment face formed on one arm of a bell crank lever 76 fulcrumed at 77 on the toe supporting post 40 9, the other arm of the bell crank lever being connected with the lower end of the releasing rod 73. Movement, therefore, of the pivot member 50 by the lever 32 removes the screw 75 from the abutment face and permits the bell crank to be rocked by a spring 45 pressed plunger 78 mounted in a bore in the toe rest supporting post, thus removing the rod 73 from the roll and allowing the lock to operate. Prior to the movement of the 50 jack beneath the leveling roll the height gage is removed out of the path of the roll by mechanism not shown.

In order to rigidly support the last pin during the operation of the machine, and 55 prevent the splitting of the last owing to the pressure upon the shoe sole, the rod 60 is automatically locked during the operation of the machine, thus rigidly supporting the last pin carrier at two points and preventing any tilting movement of the same. As 60 illustrated in Fig. 4 of the drawings, the slide rod 60 extends downwardly and passes through a guide passage formed in a clamping block 80 fulcrumed at 80. The rod is supported by a spring 81 attached at its 65 lower end to the rod and at its upper end to the clamping block, and coöperating means are provided for limiting the height to which the rod 60 is elevated by the spring. Within the clamping block 80 is a rotary 70 cam or clamping member 83 which is provided with an arm 84 provided with a cam roll 85 journaled upon its free end and connected by a spring 86 with the clamping block 80, the spring normally tending to depress the arm and cause the clamping member 83 to engage with and clamp the rod 60. When the jack is retracted or in a position of presentation a stationary cam 87 secured to the frame of the machine acts on 75 the cam roll 85 and removes the clamping member 83 from engagement with the rod, thus allowing the spring 81 to maintain the rod in an elevated position. After the shoe has been positioned upon the last pin, and 80 has been jacked by the combined action of the heel clamp 5, last pin 3, and toe rest 1, the jack, as a whole, is advanced during the operation of the machine by swinging it about the fulcrum 21 to move the shoe beneath the leveling roll 23 and at the initial part of this movement the cam roll 85 is released by the stationary cam 87 and allows the clamping member to be moved by its spring 86 into engagement with the slide 85 rod.

A modified construction for locking the slide rod in place is illustrated in Figs. 6 and 7. In this construction the slide rod is provided with teeth 90 which mesh with a toothed pinion 91 secured to a shaft 92 journaled in a block 93 through which the slide rod passes. The block 93, similar to the prior construction, is centered upon the fulcrum 30, and in the modified construction a counter-balance 94 is provided to balance the weight of the several parts and allow the block to be turned readily on the fulcrum when the slide rod is adjusted to different heights. Also attached to the shaft 92 is a friction disk 95 which is arranged at intervals to contact with a brake shoe 96 and so hold the friction disk from further rotation and lock the slide rod during the leveling operation. The brake shoe 96 is 105 normally retained in an operative position when the jack is retracted by a spring 97, and the shoe is provided with a stop pin 98 which projects over an extension 99 of the frame, and is held in contact with the upper 110 surface thereof by the spring 97. The slide rod is normally elevated in this construction by a coil spring 100 secured to and surrounding the shaft 92. In operation of this modified construction the slide rod is moved 115 120 125 130

in opposition to the spring 100 until the shoe has been jacked by the combined action of the heel clamp, last pin and toe rest, as previously described. During the movement of the slide rod through the clamping block the pinion and friction disk will be turned freely, the brake shoe at this time being held out of contact with the disk by the joint action of the stop pin 98 and extension 99. In the preliminary movement of the jack, as a whole, the stop 98 will be moved from the extension 99 so that the brake shoe will engage the friction disk at that portion of its periphery which has been brought opposite in its rotation due to the movement of the slide rod, and thereby hold the rod and its associate parts in the required position.

In order to determine the height to which the slide rod is elevated, and thereby insure a predetermined definite relation between the last pin and heel clamp, devices are provided which comprise a cam roll 102 journaled upon the slide rod and projecting within a recess formed as an inverted V in an enlarged portion of the upwardly extending arm 25 of the heel clamp. When the slide rod is released by the clutch member it is elevated by the spring until the roll 102 contacts with the upper face 103 of the recess along which it travels until the cam roll reaches the apex of the V, whereupon the movement of the last pin carrier in this direction is stopped.

The jack is conveniently actuated by a worm gear segment 105 which is adjustably connected to the jack proper and which meshes with a driving worm 106 secured to a drive shaft 107. The shaft 107 is driven from any suitable type of gearing comprising a reversing device actuated as the jack reaches each end of its stroke in order that the shaft may be rotated alternately in opposite directions to oscillate the jack backward and forward beneath the leveling roll. As the driving and reversing means form no part of the present invention, and may be of any suitable construction, they are not shown in connection with the present invention. In order to vary the relative traverse of the roll and jack in accordance with the adjustment of the jack, however, it is found convenient to vary the time at which the reversal of movement of the jack takes place. To this end the worm segment 105 is connected with a rod 110 through a floating link 111 movable between opposed surfaces 112 and 113 positioned a varying distance apart in order that the height of a roller 114 on the floating link shall introduce more or less lost motion into the driving connections, and correspondingly alter the time at which the reversal of motion takes place. The opposed surfaces are arranged, as shown in Fig. 5, at

an inclination to one another, the widest part being at the uppermost extremities. The floating link 111 is coupled at its upper end to the rod 110 connected with the reversing mechanism, while its lower end is connected through a link 115 to the worm segment 105. In order to control the position of the cam roll 114 in accordance with the adjustment of the jack, the lower end of the link 111 is provided with a pulley 116 about which passes a cord or band 117 attached at one end to a bracket 118 secured to the machine frame and projecting above the pulley 116. From the pulley 116 the cord passes over a second pulley 120 journaled upon the segment 105 and centered at the same point at which the link 115 is connected to the segment. From the pulley 120 the cord passes to one end of a segment 121 that forms a portion of the upwardly extending arm 25 carrying the heel gage. It will thus be seen that as the heel gage is moved a greater or less extent, depending upon the size of the shoe being jacked the segment 121 will be correspondingly turned and more or less of the cord passed about the pulleys 120 and 116. This will lower the floating link 111 more or less and vary the lost motion to be introduced into the connection, thus shortening or lengthening the time between the reversals of the mechanism.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:—

1. A shoe supporting jack, having, in combination, a toe post and a heel post relatively movable toward and from one another, and mechanism for automatically positioning the shoe upon the jack in a predetermined vertical position with relation to the operating tool and for clamping the shoe in its adjusted position.

2. A shoe supporting jack, having, in combination, a toe post and a heel post relatively movable toward and from one another, a single jacking lever, and operative connections for causing a continued movement of the lever to first relatively move the toe and heel posts to adjust the shoe upon the jack in a predetermined relation to the operating tool and to next clamp the shoe in its adjusted position.

3. A shoe supporting jack, having in combination, a toe post, a heel clamp arranged to engage with the heel seat of the sole, a last pin, and mechanism for actuating the last pin to simultaneously move opposite

ends of the shoe into engagement with the toe post and heel clamp to clamp the shoe in the jack.

4. A shoe supporting jack, having, in combination, a toe post and a coöperating last pin for supporting a lasted shoe, a heel gage, and mechanism for successively moving the heel gage to contact with the heel portion of the shoe and move the shoe into engagement with the toe post, for locking the heel gage in this position, and for thereafter moving the last pin to clamp the shoe in the jack.

5. A shoe supporting jack, having, in combination, a toe post, a last pin, a heel gage, and a single jacking lever constructed and arranged to automatically and successively actuate the heel gage to position the shoe in the jack and thereafter actuate the last pin to clamp the shoe in the jack.

6. A shoe supporting jack, having, in combination, a toe post, a last pin, means for yieldingly supporting the last pin, means for actuating the last pin to clamp the shoe upon the jack, and means for locking the last pin in position after the shoe is clamped upon the jack.

7. A shoe supporting jack, having, in combination, a toe post, a last pin, means for yieldingly supporting the last pin, means for actuating the last pin to clamp the shoe upon the jack, and means actuated by the movement of the jack beneath the leveling device to lock the last pin in position.

8. A shoe supporting jack, having, in combination, a toe post, a heel gage, a jacking lever operatively connected with the heel gage and arranged to actuate the heel gage to move the toe of the shoe into engagement with the toe post, and mechanism for locking the heel gage in position when further movement of the shoe toward the toe post is prevented.

9. A shoe supporting jack, having, in combination, a toe post, a last pin, a jacking lever fulcrumed between its ends and operatively connected at one end with the heel gage to actuate the heel gage and move the shoe into engagement with the toe post, means for locking the heel gage in position, and means for thereafter causing the jacking lever to fulcrum about its operative connection with the heel gage to actuate the last pin and clamp the shoe upon the jack.

10. A shoe supporting jack, having, in combination, a toe post, a last pin carrier, means for yieldingly supporting the last

pin carrier, mechanism for rocking the carrier about the support, and mechanism actuated by the movement of the jack beneath the operating tool to positively lock the yielding support and rigidly support the last pin carrier. 60

11. A shoe supporting jack comprising a toe post fulcrumed at its lower end, a heel post, adjusting mechanism for causing a relative movement of the toe and heel posts, actuating mechanism for rocking the toe post about the fulcrum, and mechanism for controlling the reversal of movement of the actuating mechanism comprising a link, a pair of opposed stop members, and connections between the link and adjusting mechanism for varying the position of the link with relation to the stop members. 75

12. A shoe supporting jack comprising toe and heel posts, adjusting mechanism for causing a relative movement of the toe and heel posts, a link, a pair of opposed stop faces inclined to one another and arranged to operatively engage with the link at predetermined intervals, and connections between the link and jack adjusting mechanism to adjust the position of the link with relation to the stop faces and vary the time at which the link engages with the stop faces. 80

13. A shoe supporting jack comprising a last pin carrier, a slide rod supporting the carrier, a clamping member through which the rod passes, and mechanism for automatically locking the rod against movement relative to the clamping member to rigidly support the last pin carrier. 90

14. A shoe supporting jack comprising a last pin carrier, a rod supporting the carrier, a clamping member through which the rod passes, a cam, and mechanism actuated by the movement of the clamping member to operate the cam and lock the rod in the clamping member. 95

15. A shoe supporting jack, having, in combination, a toe post fulcrumed about its lower end, a heel post, and a heel clamp arranged to engage with the heel seat of the sole and fulcrumed about an axis located nearer to the sole than the axis of the toe post to cause the toe post and heel clamp to move in different paths. 105
